CLAIM

The ornamental design for a reverse vending machine for empty beverage containers, as shown and described.

DESCRIPTION

FIG. 1 is a perspective view of a reverse vending machine for empty beverage containers showing my new design;
FIG. 2 is a front elevation view thereof;
FIG. 3 is a right side elevation view thereof; and,
FIG. 4 is a left side elevation view thereof.

The broken line showing of the wooden skid on FIGS. 1-4 is for illustrative purposes only and forms no part of the claimed design.
